Primary Examiner — R. Johnson(74) *Attorney, Agent, or Firm* — Hellmuth and Johnson, PLLC(57) **CLAIM**

The ornamental design for menstrual underpants, as shown and described.

DESCRIPTION

FIG. 1 is a perspective view of menstrual pants showing my new design in use;

FIG. 2 is a front perspective view thereof;

FIG. 3 is a front elevational view thereof; the rear view being identical thereof;

FIG. 4 is a top plan view thereof;

FIG. 5 is a bottom plan view thereof;

FIG. 6 is a side view thereof;

FIG. 7 is a sectional view thereof, taken along line 7-7 in FIG. 3; and,

FIG. 8 is a sectional view thereof, taken along line 8-8 in FIG. 3.

The broken lines in the figures represent unclaimed matter included for the purpose of illustrating environment and form no part of the claimed design.

1 Claim, 4 Drawing Sheets(56)
